UNITED STATES PATENT OFFICE

2,324,659

TELEPHONE SYSTEM

Albert E. Woodruff, Oak Park, Ill., assignor to
Associated Electric Laboratories, Inc., Chicago,
Ill., a corporation of Delaware

Application December 22, 1941, Serial No. 423,889

8 Claims. (Cl. 179—28)

The present invention relates to telephone systems and more particularly to improved coupling equipment for completing telephone connections between stations of the same type or of different types.

Telephone systems provided on ships and other vehicles frequently comprise stations of both the battery type and the sound-powered or non-battery type which must be variably interconnected for communication purposes without regard to the types of the individual stations.

Accordingly the principal object of the present invention is to provide in a telephone system of the type noted an improved coupling arrangement for interconnecting a plurality of stations of the same type or of different types without regard to the types of the individual stations.

Another object of the invention is to provide in a telephone system of the type noted an improved separable connecting arrangement which facilitates ready connection and disconnection of any station with respect to an established telephone connection.

The invention, both as to its organization and method of operation, together with further objects and advantages thereof, will best be understood by reference to the following specification taken in connection with the accompanying drawing, in which Figure 1 is a circuit diagram of a telephone system embodying the present invention and Fig. 2 is a circuit diagram of a modified form of the telephone system.

Referring now more particularly to Fig. 1 of the drawing there is illustrated a telephone system embodying the features of the present invention and comprising a plurality of stations A, B, etc. Preferably, the stations A, B, etc. are identical, each comprising a receiver unit including two substantially identical receivers 10, a first microphone 11 of the voltage-generating sound-wave-actuated type and a second microphone 12 of the battery vibrating-muscular-actuated type. Also each station A, B, etc. comprises first and second switches 13 and 14, first and second separable connectors 15 and 16, and a circuit network for connecting the receivers 10 and the microphones 11 and 12 to the first connector 15.

Each of the first connectors 15 is in the form of a plug of the tip-ring-sleeve type; and each of the second connectors 16 is in the form of a jack of the tip-ring-sleeve type. Preferably, each of the receivers 10 is of the construction of that disclosed in U. S. Patent No. 2,241,105, Woodruff and Horlacher, granted May 6, 1941; each of the microphones 11 is of the construction of that

disclosed in the above-mentioned Woodruff and Horlacher patent; while each of the microphones 12 is of the construction of that disclosed in U. S. Patent No. 2,252,748, Woodruff and Horlacher, granted August 19, 1941.

Also the telephone system comprises a coupling network including a tip bus 21, a ring bus 22, a sleeve bus 23, a coupling transformer 24 and a source of current supply in the form of a battery 25. The tip bus 21, the ring bus 22 and the sleeve bus 23 are respectively connected to the ring, the tip and the sleeve of each of the jacks 16. The coupling transformer 24 includes a primary winding 26 and a secondary winding 27. The secondary winding 27 is connected in series relation with a condenser 28 across the tip bus 21 and the ring bus 22; while the primary winding 26 is connected in series relation with the battery 25 across the tip bus 21 and the sleeve bus 23.

Considering now the operation of the telephone system, in order to complete a connection from any one of the stations A, B, etc. to the coupling network, it is only necessary to insert the associated plug 15 into the associated jack 16, whereby the two receivers 10 are connected in multiple by way of the tip and the ring of the plug 15 and the tip and the ring of the plug 16 to the tip bus 21 and the ring bus 22. At this time the microphone 11 may be operatively connected to the tip bus 21 and the ring bus 22 by operating the switch 13; this circuit extending from the microphone 11 by way of the switch 13, the tip and the ring of the plug 15 and the tip and the ring of the jack 16 to the tip bus 21 and the ring bus 22. Similarly, the microphone 12 may be operatively connected to the tip bus 21 and the sleeve bus 23 by operating the switch 14; this circuit extending from the microphone 12 by way of the switch 14, the tip and the sleeve of the plug 15 and the tip and the sleeve of the jack 16 to the tip bus 21 and the sleeve bus 23.

Now assume that the stations A and B are operatively connected to the coupling network for communication purposes. When the person at the station A speaks he may operate the switch 13, whereby the microphone 11 generates a signal voltage which is impressed by way of the previously traced circuit between the tip bus 21 and the ring bus 22. The signal voltage impressed between the tip bus 21 and the ring bus 22 is conducted by way of the previously traced circuit to the multiple connected receivers 10 at both the station A and the station B. On the other hand, when the person at the station A speaks he may operate the switch 14, whereby

the microphone 12 is supplied with current over the previously traced circuit including the battery 25, the primary winding 26 of the coupling transformer 24, the tip bus 21 and the sleeve bus 23. Accordingly the microphone 12 produces a signal voltage which traverses the primary winding 26 of the coupling transformer 24 and causes a corresponding signal voltage to be induced in the secondary winding 27 of the coupling transformer 24. The signal voltage induced in the secondary winding 27 of the coupling transformer 24 is impressed by way of the condenser 28 between the tip bus 21 and the ring bus 22. The signal voltage impressed between the tip bus 21 and the ring bus 22 is conducted by way of the previously traced circuit to the multiple connected receivers 10 at both the station A and the station B.

Accordingly it will be readily understood that the person at the station A may utilize either the microphone 11 or the microphone 12 in order to cause the multiple connected receivers 10 at the station B to respond. Similarly the person at the station B may utilize either the microphone 11 or the microphone 12 in order to cause the multiple connected receivers 10 at the station A to respond. Further it will be readily understood that other stations may be connected to the coupling network, which stations may be entirely of the battery type or of the sound-powered type, as noted above; and that the receivers at each of the stations connected to the coupling network will respond to the operation of the microphone at any one of the stations regardless of the type of microphone utilized.

At this point it is noted that, when the person at any station, such, for example, as the station A, is not utilizing the microphones 11 and 12, the respectively associated switches 13 and 14 will occupy their open positions in order to minimize losses in the system and to prevent unnecessary loading of the coupling network and the consequent reduction in the amplitude of the signal voltage impressed between the tip bus 21 and the ring bus 22.

Referring now more particularly to Fig. 2 of the drawing there is illustrated a modified form of the telephone system embodying the features of the present invention and comprising a plurality of stations X, Y, etc. Preferably, the stations X, Y, etc., are identical, each comprising a receiver unit including two substantially identical receivers 30, a first microphone 31 of the voltage-generating sound-wave-actuated type and a second microphone 32 of the battery vibrating-muscular-actuated type. Also each station X, Y, etc. comprises first and second switches 33 and 34, first and second separable connectors 35 and 36, and a circuit network for connecting the receivers 30 and the microphones 31 and 32 to the first connector 35.

Each of the first connectors 35 is in the form of a plug of the tip-ring-sleeve type; and each of the second connectors 36 is in the form of a jack of the tip-ring-sleeve type. Preferably, each of the receivers 30 is of the construction of that disclosed in U. S. Patent No. 2,241,105, Woodruff and Horlacher, granted May 6, 1941; each of the microphones 31 is of the construction of that disclosed in the above-mentioned Woodruff and Horlacher patent; while each of the microphones 32 is of the construction of that disclosed in U. S. Patent No. 2,252,748, Woodruff and Horlacher, granted August 19, 1941.

Also each station X, Y, etc. comprises a coupling transformer 44 and a source of current supply in the form of a battery 45. The coupling transformer 44 includes a primary winding 46 and a secondary winding 47. The secondary winding 47 is adapted to be connected by way of a pair of contacts 37 carried by the jack 36 across the tip and the ring of the jack 36; while the primary winding 46 is connected in series relation with the battery 45 across the tip and the sleeve of the jack 36.

Also the telephone system comprises a coupling network including a tip bus 41 and a ring bus 42. The tip bus 41 and the ring bus 42 are respectively connected to the tip and the ring of each of the jacks 36.

Considering now the operation of the telephone system, in order to complete a connection from any one of the stations X, Y, etc. to the coupling network, it is only necessary to insert the associated plug 35 into the associated jack 36, whereby the two receivers 30 are connected in multiple by way of the tip and the ring of the plug 35 and the tip and the ring of the plug 36 to the tip bus 41 and the ring bus 42. Also when the plug 35 is inserted into the jack 36 the pair of contacts 37 is closed, thereby operatively to connect the secondary winding 47 of the coupling transformer 44 across the tip and the ring of the jack 36 and consequently across the tip bus 41 and the ring bus 42. At this time the microphone 31 may be operatively connected to the tip bus 41 and the ring bus 42 by operating the switch 33; this circuit extending from the microphone 31 by way of the switch 33, the tip and the ring of the plug 35 and the tip and the ring of the jack 36 to the tip bus 41 and the ring bus 42. Similarly an operating circuit may be completed for the microphone 32 by operating the switch 34; this circuit extending from the microphone 32 by way of the switch 34, the tip and the sleeve of the plug 35 and the tip and the sleeve of the jack 36 and the primary winding 46 of the coupling transformer 44 to the terminals 45 of the battery 45.

Now assume that the stations X and Y are operatively connected to the coupling network for communication purposes. When the person at the station X speaks he may operate the switch 33, whereby the microphone 31 generates a signal voltage which is impressed by way of the previously traced circuit between the tip bus 41 and the ring bus 42. The signal voltage impressed between the tip bus 41 and the ring bus 42 is conducted by way of the previously traced circuit to the multiple connected receivers 30 at both the station X and the station Y. On the other hand, when the person at the station X speaks he may operate the switch 34, whereby the microphone 32 is supplied with current over the previously traced circuit including the battery 45 and the primary winding 46 of the coupling transformer 44. Accordingly the microphone 32 produces a signal voltage which traverses the primary winding 46 of the coupling transformer 44 and causes a corresponding signal voltage to be induced in the secondary winding 47 of the coupling transformer 44. The signal voltage induced in the secondary winding 47 of the coupling transformer 44 is impressed by way of the contacts 37 of the jack 36 between the tip bus 41 and the ring bus 42. The signal voltage impressed between the tip bus 41 and the ring bus 42 is conducted by way of the previously traced

circuit to the multiple connected receivers 30 at both the station X and the station Y.

Accordingly it will be readily understood that the person at the station X may utilize either the microphone 31 or the microphone 32 in order to cause the multiple connected receivers at the station Y to respond. Similarly the person at the station Y may utilize either the microphone 31 or the microphone 32 in order to cause the multiple connected receivers 30 at the station X to respond. Further it will be readily understood that other stations may be connected to the coupling network, which stations may be entirely of the battery type or of the sound-powered type, as noted above; and that the receivers at each of the stations connected to the coupling network will respond to the operation of the microphone at any one of the stations regardless of the type of microphone utilized.

At this point it is noted that, when the person at any station, such, for example, as the station X, is not utilizing the microphones 31 and 32, the respectively associated switches 33 and 34 will occupy their open positions in order to minimize losses in the system and to prevent unnecessary loading of the coupling network and the consequent reduction in the amplitude of the signal voltage impressed between the tip bus 41 and the ring bus 42. More specifically, when the switch 34 occupies its open position the previously traced circuit, including the battery 45, for energizing the primary winding 46 of the coupling transformer 44 is interrupted, whereby the effective impedance of the secondary winding 47 of the coupling transformer 44, connected by way of the contacts 37 of the jack 36 across the tip bus 41 and the ring bus 42, is rendered exceedingly high.

While two embodiments of the invention have been disclosed, it will be understood that various modifications may be made therein which are within the true spirit and scope of the invention.

What is claimed is:

1. A telephone system comprising a plurality of stations; each of said stations including first and second separable connectors, a receiver, a first microphone of the voltage-generating sound-wave-actuated type, a second microphone of the battery vibrating-muscular-actuated type, and a circuit network operatively connecting said receiver to said first connector and selectively controllable operatively to connect either said first microphone or said second microphone to said first connector, and a coupling network operatively interconnecting said second connectors.

2. A telephone system comprising a plurality of stations; each of said stations including first and second separable connectors, a receiver, a first microphone of the voltage-generating sound-wave-actuated type, a second microphone of the battery vibrating-muscular-actuated type, first and second switches, and a circuit network operatively connecting said receiver to said first connector and selectively controllable by said first and second switches respectively operatively to connect said first and second microphones to said first connector; and a coupling network operatively interconnecting said second connectors.

3. A telephone system comprising a plurality of stations; each of said stations including first and second separable connectors of the matched three-terminal type, a receiver connected across the first and second terminals of said first connector, a first microphone of the voltage-generating sound-wave-actuated type, a first switch oper-

ative to connect said first microphone across the first and second terminals of said first connector, a second microphone of the battery vibrating-muscular-actuated type, and a second switch operative to connect said second microphone across the second and third terminals of said first connector; and a coupling network operatively interconnecting the first and second and third terminals of said second connectors.

4. A telephone system comprising a plurality of stations; each of said stations including a plug of the tip-ring-sleeve type, a receiver, a first microphone of the voltage-generating sound-wave-actuated type, a second microphone of the battery vibrating-muscular-actuated type, and a circuit network operatively connecting said receiver across the tip and the ring of said plug and selectively controllable operatively to connect said first microphone across the tip and the ring of said plug and to connect said second microphone across the tip and the sleeve of said plug; a plurality of jacks individual to said stations and of the tip-ring-sleeve type; and a coupling network operatively interconnecting the tip and ring and sleeve of said jacks.

5. A telephone system comprising a plurality of stations; each of said stations including first and second separable connectors of the matched three-terminal type, a receiver connected across the first and second terminals of said first connector, a first microphone of the voltage-generating sound-wave-actuated type, a first switch operative to connect said first microphone across the first and second terminals of said first connector, a second microphone of the battery vibrating-muscular-actuated type, and a second switch operative to connect said second microphone across the second and third terminals of said first connector; a coupling transformer provided with primary and secondary windings; a source of current supply; and a circuit network connecting the secondary winding of said coupling transformer across the first and second terminals of each of said second connectors and connecting the primary winding of said coupling transformer and said source of current supply in series relation across the second and third terminals of each of said second connectors.

6. A telephone system comprising a plurality of stations; each of said stations including a plug of the tip-ring-sleeve type, a receiver, a first microphone of the voltage-generating sound-wave-actuated type, a second microphone of the battery vibrating-muscular-actuated type, and a circuit network operatively connecting said receiver across the tip and the ring of said plug and selectively controllable operatively to connect said first microphone across the tip and the ring of said plug and to connect said second microphone across the tip and the sleeve of said plug; a plurality of jacks individual to said stations and of the tip-ring-sleeve type; tip and ring and sleeve busses respectively connected to the tip and ring and sleeve of said jacks; a coupling transformer provided with primary and secondary windings; a source of current supply; and a circuit network connecting the secondary winding of said coupling transformer across said tip bus and said ring bus and connecting the primary winding of said coupling transformer and said source of current supply in series relation across said tip bus and said ring bus.

7. A telephone system comprising a plurality of stations; each of said stations including first and second separable connectors of the matched

three-terminal type, a receiver connected across the first and second terminals of said first connector, a first microphone of the voltage-generating sound-wave-actuated type, a first switch operative to connect said first microphone across the first and second terminals of said first connector, a second microphone of the battery vibrating-muscular-actuated type, a second switch operative to connect said second microphone across the second and third terminals of said first connector, a coupling transformer provided with primary and secondary windings, a source of current supply, and a circuit network selectively controllable to connect the secondary winding of said coupling transformer across the first and second terminals of said second connector and connecting the primary winding of said coupling transformer and said source of current supply in series relation across the second and third terminals of said second connector; and a circuit network operatively interconnecting the first and second terminals of said second connectors.

8. A telephone system comprising a plurality

5 of stations; each of said stations including a plug and a jack each of the tip-ring-sleeve type, a receiver, a first microphone of the voltage-generating sound-wave-actuated type, a second microphone of the battery vibrating-muscular-actuated type, a circuit network operatively connecting said receiver across the tip and the ring of said plug and selectively controllable operatively to connect said first microphone across the tip and the ring of said plug and to connect said second microphone across the tip and the sleeve of said plug, a coupling transformer provided with primary and secondary windings, a source of current supply, and a circuit network selectively controllable to connect the secondary winding of said coupling transformer across the tip and the ring of said jack and connecting the primary winding of said coupling transformer and said source of current supply in series relation across the tip and the sleeve of said jack; and tip and ring busses respectively connected to the tip and the ring of said jacks.

ALBERT E. WOODRUFF.
